UNITED STATES PATENT OFFICE

WILHELM B. BRONANDER, OF MONTCLAIR, NEW JERSEY

FIRE EXTINGUISHER

Application filed November 11, 1929. Serial No. 406,207.

This invention relates to fire extinguishers and particularly to supports or mountings therefor.

The invention pertains more specifically to a fire extinguisher support or mounting adapted for use in motor vehicles and has for its salient object to provide a mounting so arranged that the extinguisher will normally be concealed from sight but will be readily and quickly accessible when needed.

Further objects of the invention will appear from the following specification taken in connection with the drawings which form a part of this application, and in which

15 Fig. 1 is a front elevation of a portion of the instrument board of a motor vehicle showing a fire extinguisher mounting in connection therewith;

20 Fig. 2 is a transverse sectional elevation taken through the instrument board and extinguisher mounting;

Fig. 3 is an enlarged sectional elevation similar to Fig. 2 but showing the extinguisher support swung to open position;

25 Fig. 4 is a longitudinal sectional elevation taken through the extinguisher and support;

Fig. 5 is an elevational view of the bracket or back plate on which the extinguisher is removably supported; and

30 Fig. 6 is a rear elevational view of the extinguisher and casing.

The invention briefly described consists of a supporting panel, such as an instrument board of a motor vehicle, having an opening 35 therein and a closure for the opening, the extinguisher being detachably or removably supported by or connected to the back of the closure.

Further details of the invention will appear from the following description.

In the particular embodiment of the invention illustrated in the drawings, there is shown an instrument board 10 of a motor vehicle having an opening 11 normally closed by a door or closure 12. The closure 12 is hinged at 13 and is normally maintained closed by a suitable catch 14. When closed, the door is preferably flush with the outer face of the instrument board 10. The outward movement of the door or closure is lim-

ited by a stop member 15 having a lug 16 extending laterally therefrom and adapted to engage the end edge of the opening when the door has swung outwardly to a predetermined extent. Attention is called to the fact that the member 15 extends upwardly and across the axis of the extinguisher and thus shields the hammer hereinafter described against accidental actuation.

The extinguisher may be of any desired 55 form or shape and the mounting may be constructed in any suitable manner to detachably secure the extinguisher to the back of a closure or door 12. In the form of the invention shown, the extinguisher is mounted 60 on a back plate 17 which is secured to the back of the closure and has formed thereon a pair of inwardly projecting tapered flanges 65 18 and 19.

The fire extinguisher illustrated comprises an elongated tubular container 20 70 formed of frangible material, such as glass, and having a depression 21 at the lower end thereof.

In order to protect the frangible container 75 from accidental breakage, the container is housed in and covered by a casing comprising a central or body portion 25, a bottom 26 and a cap or cover 27 which forms the top of the casing.

80 The body portion 25 consists of a cylindrical band or sleeve having outturned flanges 30 and 31 tapered longitudinally with respect to each other, as shown in Fig. 3. The body portion has a plurality of lugs or 85 lips 32 struck out from the material thereof and extending through the dome shaped bottom 26 of the casing. From the showing in Fig. 4 it will be noted that the lower peripheral portions 35 of the container are so 90 formed that they will rest on the portions 36 of the dome shaped bottom 26.

The cover or cap 27 which forms the top of the casing is provided with lugs 40 which are adapted to engage recesses or openings 41 95 formed along the upper edge of the body portion 25 and the cap is also provided with a laterally extending lug 42 which extends through a slot 43 formed in the back portion of the wall of the body portion 25. A spring 100

45 is positioned within the cap 27 and presses against the upper end of the container in order to prevent endwise movement of the container in the casing and to hold the container against the bottom 26.

In order to facilitate breaking the frangible container, a hammer having a head 48 and a shank 49 is slidably mounted in a bushing 50 carried by the bottom portion 26 of the container. In the form of the invention shown in Figs. 4 to 6 inclusive, the hammer is normally pressed by a spring 52 against the depressed portion 21 of the lower end of the container. The stop member 15 extends across the end 15 of the hammer shank 49 and prevents accidental engagement therewith.

The casing and container is secured to the bracket by means of resilient legs 60 and 61 of a U-shaped spring 62. The spring is secured to the front face of the back plate 17 by means of flanges 18 and 19 and lugs 65 and 66 formed on the flanges and extending into engagement with the spring. The upper ends of the legs 60 and 61 can slide beneath the lugs 66 to permit the legs which are bowed inwardly to be forced outwardly. In order to mount the casing and container on the back plate, the casing is positioned as shown in Fig. 3 with the legs 60 and 61 engaging between the outer surface of the band or central portion 25 of the casing and the flanges 18 and 19 of the clamping plate 17. This can be accomplished by forcing one of the legs laterally and snapping the other leg 35 into the position shown in Fig. 3 or by moving the container downwardly so that the tapered clamping plate will be positioned with its flanges behind the spring legs 60 and 61. To further secure the casing to the back plate 17 and to prevent accidental removal therefrom, a bail or loop 65 is pivoted to the end 66 of the plate and is adapted to swing over the casing cover 27 and embrace the cover.

45 In order to use the device, the closure or door 12 is opened by pulling on a handle or button 70 and the container is removed from the back plate or support by sliding it longitudinally or merely by grasping it firmly and

pulling it away from the bracket and then the shank 49 of the hammer is engaged against any suitable object and forced inwardly, breaking the lower end of the frangible container. The bottom 27 of the casing has a plurality of perforations or openings 55 to permit the fire extinguishing fluid to pass therethrough.

From the foregoing description it will be evident that a simple, practical and effective support or mounting for a fire extinguisher has been designed and that the extinguisher will be concealed under normal conditions but can be easily and quickly removed from its support when desired.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. In combination, a supporting panel having an opening therein and a closure for said opening pivoted on a substantially horizontal hinge and arranged to swing inwardly and downwardly, means for limiting the opening movement of said closure, and a fire extinguisher detachably supported by and resiliently carried by the inner surface of said closure whereby said extinguisher will be readily accessible when the closure is opened.

2. In combination, a supporting panel having an opening therein and a closure for said opening pivoted on a substantially horizontal hinge and arranged to swing inwardly and downwardly, means for limiting the opening movement of said closure, and a fire extinguisher detachably supported on the back of said closure and resilient means on the closure for supporting said extinguisher, said means being arranged to release the extinguisher when said extinguisher is pulled laterally.

WILHELM B. BRONANDER.
